INJECTION HATCHET FOR TREATING
DISEASED TREES

Michael Newton, 149 Peterson Road,
Philomath, Oreg.

Filed July 14, 1967, Ser. No. 7,804

Term of patent 14 years

(Cl. D35—2)

FIG. 1

FIG. 2

FIG. 3

FIG. 4

FIG. 5

FIG. 6

FIG. 7

FIGURE 1 is a perspective view of an injection hatchet for treating diseased trees showing my new design;

FIGURE 2 is a side elevational view thereof;

FIGURE 3 is a bottom plan view thereof;

FIGURE 4 is a side elevational view thereof showing the opposite side from that shown in FIGURE 2;

FIGURE 5 is a top plan view thereof;

FIGURE 6 is a front end view thereof; and

FIGURE 7 is a rear end view thereof.

I claim:

The ornamental design for an injection hatchet for treating diseased trees, substantially as shown.
